CONVEYER APPARATUS

Clark Scholl, Springfield, Ohio, assignor to The Steel Products Engineering Company, Springfield, Ohio, a corporation of Ohio

Application September 30, 1939, Serial No. 297,247

3 Claims. (Cl. 198—213)

This invention relates to combustion apparatus and more particularly to stokers such as for the feeding of solid fuel from a bin to a retort.

A principal object of the invention is the provision of a power driven stoker for feeding solid fuel from a bin to a retort which is entirely positioned between the bin and the retort, which provides for feeding the fuel along a substantially horizontal plane and with a minimum of power, and which is of a relatively simple construction providing for great ease in the assembly of the apparatus and in taking apart individual parts thereof for the purpose of making repairs and the like.

A further object is the provision of such stoking apparatus in which the entire drive mechanism is readily accessible from the exterior of the feeding apparatus.

A further object is to provide a feeding apparatus in which a common power drive means effects the driving of a plurality of conveyer worms and is connected to the worms by a plurality of enclosed drive mechanisms each independently accessible from the exterior of the feeding apparatus.

A still further object is to provide a stoker device in which the fuel is transferred from one conveyer worm to another with a minimum power requirement and a minimum of churning and crushing of the fuel.

Other objects and advantages will be apparent from the following description, the appended claims and the accompanying drawings.

In the drawings,

Fig. 1 is a plan view, partly broken away, of a fuel feeding and stoking apparatus constructed in accordance with the present invention;

Fig. 2 is a side elevational view of the apparatus shown in Fig. 1;

Fig. 3 is a horizontal sectional view taken substantially on the line 3—3 of Fig. 2; and

Fig. 4 is a transverse sectional view taken substantially on the line 4—4 of Fig. 1.

Referring to the drawings which illustrate a preferred embodiment of the invention, the reference numeral 10 designates a bin having an outer wall 10a for receiving a quantity of solid fuel such as coal or the like adapted to be fed to a retort 11 positioned in spaced relation with respect to the bin. In accordance with the present invention the entire stoking apparatus is located between the bin and the retort and comprises a conveyer worm 12 which feeds the fuel from the bin 10 to a transfer chamber or box

13 positioned intermediate the bin and retort and a second conveyer worm 14 which feeds the fuel from the transfer chamber 13 to the retort 11. Each of the worms 12 and 14 is individually mounted in the transfer chamber 13 and is independently driven from a common power drive means mounted on the top of the transfer chamber. The two feed worms are preferably arranged to lie substantially within a single horizontal plane, the transfer chamber also occupying the same general plane to provide for the easy and effective feeding of the fuel from the bin to the transfer chamber, and the lateral transfer therethrough and the feeding therefrom into the retort.

The conveyer worm 12 comprises a worm shaft 15 and a flight 16 for feeding fuel forwardly. It extends into and across the bin 10, adjacent the bottom thereof and is supported at its end

20 within the bin by a section of pipe or tubing 17 mounted on brackets 18 adjacent the remote wall 10a of the bin. A trough 19 having an arcuate or V-shaped cross-section may be positioned along the lower side of the worm 12 to assist in feeding a controlled quantity of fuel forwardly from the bin and to provide for ready removal and replacement of the feed worm without removing the fuel from the bin as is more fully described in applicant's copending application, now

25 30 Patent No. 2,355,244, patented August 8, 1944, assigned to the same assignee as the present invention. As is also described in this co-pending application, the portion of the feeding flight 16 which is received within the bin is preferably of a tapered construction as shown providing for feeding a controlled quantity of fuel with a minimum of churning and crushing of the fuel.

The conveyer worm 12 passes outwardly from the bin through a suitable opening provided in the inner wall 20 thereof and extends through a conveyer tube 21 to the transfer chamber 13. A removable shear plate 22 is provided adjacent the worm outlet of the bin and the conveyer tube 21 which encloses the conveyer worm between the bin 10 and transfer chamber 13 is provided with a suitable clean-out opening adjacent the shear plate 22. A cap member 23 preferably formed integrally with shear plate 22 is removably retained in position by a hand screw 24 and provides for closing the clean-out opening in the conveyer tube.

To provide for individually supporting and driving the end of the conveyer worm 12 that is received within the transfer chamber 13, a housing member 25 is mounted on an end wall

29 of the transfer chamber and provides a bearing for rotatably supporting a short drive shaft 30. The drive shaft 30 has a non-circular portion 31 of reduced diameter which extends into the interior of the transfer chamber and is received within a cooperating non-circular recessed head 32 provided on the end of the worm shaft 13 and thus provides a detachable drive and support for the end of the worm shaft received within the transfer chamber. A pin 33 provides for taking the thrust load between the drive shaft 30 and the worm shaft 15, and the shaft 30 thus provides a continuation of the worm shaft which extends outwardly from the side of the transfer chamber that is most remote from the bin 10 and terminates within an enlarged portion 34 of the housing 28. A sprocket 35 providing for driving the shaft 30 and the conveyer worm 12 is fixed to the end of the drive shaft 30 within the enlarged housing portion 34, and a thrust bearing 36 is provided between the sprocket and the housing portion 28 for taking the end thrust caused by the conveyer worm during the operation thereof and transmitted to the thrust bearing through the drive shaft 30. The housing portion 34 is open at its outer side to provide for ready access to the drive mechanism therein from the exterior of the apparatus and a removable closure member 37 provides for normally closing the open outer side of the housing.

The second feed worm 14 comprises a worm shaft 41 and a flight 42 for feeding fuel forwardly and is received within the transfer chamber 13 with the worm shaft 41 positioned laterally of the worm shaft 15 and extending in spaced overlapping relation with respect thereto. A housing 45 providing a bearing for rotatably supporting a second drive shaft 46 is mounted on the outer side of the wall 47 of the transfer chamber and the shaft 46 is provided with a recessed portion 48 adapted to receive and support the end of the worm shaft 41. A suitable detachable driving connection is provided between the drive shaft 46 and the worm shaft 41, and the drive shaft thus provides a continuation of the worm shaft which extends outwardly from the side of the transfer chamber which is most remote from the retort 11. A sprocket 50 providing for driving the conveyer worm 14 is keyed to the drive shaft 46 within the housing 45 and a thrust bearing 51 also mounted within the housing 45 provides for taking the end thrust of the worm. As will be clear from the foregoing, both thrust bearings 36 and 51, as well as the respective drive sprockets, are located in a protected position within a chamber which is entirely closed off from the path of travel of the fuel. A plate 52 removably attached to the housing 45 provides for normally closing the housing and the drive sprocket therein, and also serves as a support for the thrust bearing 51.

In the preferred embodiment of the invention the ends of the conveyer worms 12 and 14 which are received within the transfer chamber 13 are positioned in substantially the same horizontal plane and a horizontally arranged transfer passage 55 defined by the walls 29 and 41 of the transfer chamber provides for feeding the fuel from the conveyer worm 12 to the conveyer worm 14. As shown the shape of this passageway 55 is such that the fuel will freely move in a lateral direction from the first worm to the second worm under the action of the fresh supply of

fuel that is being continuously advanced by the first conveyer worm 12 during the operation of the feeding apparatus. Preferably the wall 29 is relieved as shown to make for easier and more uniform introduction of the fuel into the second conveyer worm. To assist in feeding the fuel laterally through the passageway 55 of the transfer chamber with a minimum of churning and crushing of the fuel and also to prevent the packing of fuel in the corner of the transfer chamber adjacent the end of the worm shaft 15, a reverse flight 56 is provided on the end of the worm shaft 15 adjacent the end wall 29 of the transfer chamber. The reverse flight 56 tends to feed the fuel in the opposite direction from the forwardly feeding flight 16 and thus assists in causing the fuel to move laterally through the passage 55 while avoiding packing and crushing of the fuel in the corner of the transfer chamber. The forward feeding flight 16 and the reverse flight 56 terminate in a spaced relationship providing for free lateral feeding of the fuel with a minimum of churning and crushing of the fuel. The cross-sectional dimensions of the transfer passage are substantially greater than that of the conveyer tubes and hence no obstruction is afforded to the fuel during the transfer from one tube to the other and the action of conveyer flight 42 in picking up the relatively more slowly moving fuel therefrom is facilitated. To further eliminate any chance of packing or crushing of the fuel within the transfer chamber 13 the conveyer worm 14 preferably removes the fuel from the transfer chamber at a faster rate than the fuel is fed into the chamber by the conveyer worm 12. For this purpose the conveyer worm 14 may have a greater capacity than the worm 12 or the worm shaft 41 may be rotated at a greater speed than the worm shaft 15. A conveyer tube 60 encloses the conveyer worm 14 between the transfer chamber 13 and the retort 11. To adapt the apparatus to different installations in which the distance between the bin 10 and retort 11 varies the conveyer tube may be provided in a plurality of sections 61 joined together by a suitable removable clamping device 62, it being understood that as many sections 61 will be provided as is required for a given installation. A suitable clamping device 63 provides for removably attaching the conveyer tubing to the retort 11. The retort is illustrated as being of the under-feed type and is provided with an opening 65 through which the fuel is fed upwardly by the conveyer worm 14. Suitable tuyères 66 for supplying combustion air to the fuel are also preferably provided in the retort.

As described above a common power drive means is mounted on the transfer chamber 13 and is independently connected to the worm conveyers 12 and 14 to effect the operation thereof. As shown a gear housing 68 having suitable reduction gearing provided therein is supported above the closed wall of transfer chamber 13 and an electric motor 69 is resiliently mounted on the top of the gear housing 68 and is connected to the gearing within the housing by means of a belt 70 which runs over a pulley 71 mounted on the motor shaft and a pulley 72 mounted on a shaft 73 extending outwardly from the gear housing. A housing member 74 is mounted upon the top of the portion 34 of the housing 28 and provides a support for the gear casing 68 to which it is attached. A horizontal drive shaft 75 having its axis parallel with the

drive shaft 30 and the worm shaft 15 extends from the gear housing 68 into the housing 74, and a sprocket 76 is attached to the shaft 75 within the housing 74. A suitable opening is provided between the housing members 28 and 74 and a chain 77 extends around the sprocket 76 in housing 74 and sprocket 35 in the portion 34 of housing 28 to provide a driving connection between the power drive means and the worm conveyer 12. The removable cover plate 37 extends upwardly and normally closes the housing 74 as well as the housing portion 34 but provides for ready access to the drive mechanism positioned therein from the exterior of the apparatus upon removal of the cover plate.

The drive shaft 75 also extends outwardly from the opposite side of the gear housing 68 with its axis parallel with the axis of the drive shaft 46 and the worm shaft 41 as indicated at 80 and terminates within a housing member 81 mounted on the top of the housing member 45. A sprocket 82 is attached to the shaft portion 80 within the housing 81 and a chain 83 extends through an opening provided between the housing members 81 and 45 and connects the sprocket 82 with the sprocket 50 within the housing 45 to provide a driving connection between the power drive means and the worm conveyer 14. A plate 84 is removably attached to the outer side of the housing 81 to normally close the housing but permit ready access thereto from the exterior of the apparatus. The power drive means is thus independently connected to the two worm conveyers and the drive mechanisms are individually accessible from outside of the apparatus.

The power drive means also provides for supplying air under forced draft to the tuyères of the retort. For this purpose a blower 88 is mounted on one side of the gear housing 68 and is provided with an air duct 89 which extends from the blower to the retort 11 and provides for supplying air to the tuyères of the retort. A second air duct 90 similarly connected to the opposite side of the retort is of such length that the closed end will just come to the outside of the largest furnace in which this unit might be installed and is provided for the purpose of cleaning out the siftings and riddlings that enter the plenum chamber through the tuyère openings and which should be cleaned out once each season, or oftener if necessary, in order to prevent restriction of the air to the fuel. The shaft 73 which is operatively connected with the motor 69 by means of the belt 70 and pulleys 71 and 72 extends from the gear housing 68 into the blower 88 and provides for operating the blower under the control of the motor 69. A clutch and change speed gearing member 91 provides for disconnecting the gearing within the housing 68 from the shaft 73 to permit selective operation of the blower alone or of both the blower and of the fuel feeding apparatus at a predetermined desired rate of feed. A housing 95 is positioned adjacent the blower 88 and air duct 89 and encloses suitable mechanism which provides for regulation of the blower to supply combustion air under proper predetermined conditions of pressure.

Upon operation of the motor 69 and actuation of the clutch lever 91 to cause operation of the reduction gearing within the housing 68 the worm conveyer 12 will rotate to receive fuel from within the bin 10 and advance it forwardly to the transfer chamber 13 and the conveyer worm 14 will rotate to advance the fuel from the trans-

fer chamber to the retort 11. At the same time the blower 88 is operated to supply combustion air to the retort. The forward feeding flight 16 on the worm shaft 15 in cooperation with the reverse flight 56 on the worm shaft causes the fuel to feed laterally within the transfer chamber with a minimum of churning and crushing of the fuel and without packing of the fuel within the corners of the transfer chamber. Each of the worm shafts is independently connected with the power drive means by a drive mechanism which is separately accessible for repairs and the like. This drive mechanism, moreover, is readily accessible from the exterior of the apparatus by merely removing the cover plates 37, 52 and 84. The entire apparatus, furthermore, is of a relatively simple construction providing for assembly and dismantling thereof with great ease and a minimum of time and work. The arrangement is also such that the entire feeding operation may take place in substantially a single horizontal plane thus providing for the feeding of fuel from the bottom of the bin and to a relatively low positioned retort. All of the apparatus is positioned between the bin and the retort and, accordingly, the necessity for additional floor space beyond the furnace proper and the use of relatively long worm shafts with consequent strain and twisting therein is avoided, and the feeding of the fuel is accomplished with maximum efficiency and a minimum power requirement.

The present invention is of particular advantage with a ratchet type drive in which a ratchet mechanism within the gear casing provides for rotating the worm conveyer with an intermittent or impulse action, each impulse preferably comprising a considerable part of one complete revolution of the worm and providing a "breathing" effect in the fuel bed. Thus by the provision of relatively short worm shafts and thereby avoiding substantial torsion and consequent recoil therein under the action of the impulse drive, the operation of the ratchet drive is made more positive and the wear on the mechanism within the gear casing is substantially reduced.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A domestic stoker for withdrawing solid fuel from a bin and feeding the same forwardly to a retort to be delivered upwardly thereinto while preventing escape of fuel or dust and with a minimum of working and grinding of the fuel in transit comprising a first conveyer worm shaft extending in a straight line in a substantially horizontal plane from within the bin to a position forwardly thereof, flights on said worm shaft providing for feeding fuel forwardly, a closed conveyer tube enclosing the portion of said worm shaft forwardly of said bin preventing escape of fuel and dust therefrom and located closely adjacent the level of the bin floor, a second conveyer worm shaft having an end thereof overlapping the forward end of said first shaft and lying in the same horizontal plane therewith and in laterally spaced relation with respect thereto, said second worm shaft extending forwardly into the lower part of a

retort, flights on said second worm shaft providing for feeding fuel forwardly with sufficient pressure to deliver the fuel upwardly to said retort, a closed conveyer tube enclosing said second worm shaft and extending forwardly to said retort to maintain the fuel passage closed and sealed, an enclosed transfer chamber in substantially said same horizontal plane for receiving the adjacent ends of said conveyer tubes in sealed relation and with the overlapping worm shafts exposed therein forming a transverse substantially horizontal passageway providing for free feeding of the fuel from the flight on said first worm shaft to the flight on said second worm shaft while retaining the fuel in said same horizontal plane, means on said transfer chamber for rotatably supporting the adjacent ends of said worm shafts with extensions of said shafts extending outwardly beyond the enclosing walls of said transfer chamber respectively, power drive means mounted on said transfer chamber, and means providing separate direct connections extending downwardly respectively from said power drive means to said outwardly extended extensions of said worm shafts.

2. A domestic stoker adapted to be positioned directly upon the basement floor for withdrawing solid fuel from a bin and feeding the same forwardly to a retort to be delivered upwardly thereto while preventing escape of fuel or dust and with a minimum of working and grinding of the fuel in transit comprising a first conveyer worm shaft adapted to extend in a straight line from within the bin to an intermediate position forwardly of the bin, a second conveyer worm shaft having an end thereof overlapping the forward end of said first shaft in the same horizontal plane therewith and in laterally spaced relation with respect thereto, said second worm shaft extending forwardly from said intermediate position and into a retort, a transfer chamber at said intermediate position for receiving the adjacent ends of said shafts and having an enclosing casing defining a transverse passageway in the same horizontal plane with said worm shafts, the walls of said passageway being relieved in the direction of fuel movement providing for free lateral feeding of fuel from the flight on said first shaft to the flight on said second shaft without crushing or packing thereof, a closed conveyer tube enclosing said first worm shaft and extending from the wall of said bin to one side of said transfer chamber forming a closed and sealed passage for delivery of the fuel, a closed conveyer tube enclosing said second worm shaft and extend-

ing from the opposite side of said transfer chamber to said retort forming a closed and sealed passage for delivery of the fuel, both said tubes being located immediately adjacent the basement floor and in closely spaced relation to each other at their overlapping ends, flights on said worm shafts for developing a forward feeding pressure within said closed tubes, drive means for driving said worm shafts from the respective ends thereof, power actuated means mounted on said transfer chamber above the plane of said shafts, and separate drive members connected respectively in operative relation with said drive means from above the plane of said shafts.

3. A domestic stoker for withdrawing solid fuel from a bin and feeding the same forwardly to a retort to be delivered upwardly thereto while preventing escape of fuel or dust and with a minimum of working and grinding of the fuel in transit comprising a first conveyer worm shaft adapted to extend in a straight line from within the bin to a position forwardly thereof, a second worm shaft having an end thereof overlapping the forward end of said first worm shaft in the same horizontal plane and in laterally spaced relation with respect thereto, said second worm shaft extending forwardly in the same general direction as said first shaft and into a retort, a transfer chamber for receiving the adjacent ends of said shafts in immediately adjacent relation and having an enclosing casing defining a short transverse passageway in the same horizontal plane with said shafts of sufficient cross-sectional area to provide for free flow of fuel therethrough, a closed conveyer tube between said bin and said transfer chamber and between said transfer chamber and said retort for enclosing and sealing said respective worm shafts, flights on said first worm shaft for developing forward feeding pressure to cause the fuel to flow laterally through said transverse passageway, flights on said second worm shaft for developing a forward feeding pressure to cause the fuel to flow upwardly into said retort, each said worm shaft having a part extending outwardly beyond the adjacent end wall of said transfer chamber, power drive means mounted on the casing of said transfer chamber above said horizontal plane and having a power shaft extending outwardly from each of two opposite sides thereof in substantial alignment with said worm shaft extending parts, and means for separately connecting said power shafts with said respective worm shaft extending parts.

CLARK SCHOLL.
